GRACE M. HUTCHBY, OF LOS ANGELES, CALIFORNIA

PERMANENT WAVING PAD AND STICK APPARATUS

Application filed May 20, 1930. Serial No. 454,143.

My invention relates to an apparatus that is particularly designed for use in waving and curling hair on the human head, and the principal objects of my invention are, to provide a relatively simple, practical and inexpensive apparatus that will effect a saving of much of the time and labor that is ordinarily involved in the operations incident to the imparting of wave to the hair, further, to provide an apparatus having a plurality of hair receiving sticks or members that are mounted for rotation on the apparatus so that hair may be wound thereupon to produce the desired waves and curls, further, to provide an apparatus that will be effective in imparting uniform wave and curl to the hair and further, to provide a hair waving and curling apparatus of the character referred to that will not afford discomfort to the person whose hair is being waved and curled and the device being constructed so as to minimize the possibility of burning the hair or the head of the person whose hair is being waved and curled.

With the foregoing and other objects in view, my invention consists in certain novel features of construction and arrangement of parts that will hereinafter be more fully described and claimed and illustrated in the accompanying drawings in which:

Fig. 1 is a perspective view showing my improved hair waving apparatus in position upon the head.

Fig. 2 is a perspective view of one of the hair clamping bands of the apparatus.

Fig. 3 is a perspective view of the hair clamping band that carries the sticks or rods upon which the hair is curled.

Fig. 4 is a fragmentary elevational view partly in section and showing a ratchet wheel that is instrumental in holding the stick or rod against reverse rotary motion when hair is curled thereon.

Fig. 5 is a cross section taken on the line 5-5 of Fig. 4.

Fig. 6 is a fragmentary elevation of a portion of one of the hair clamping bands and showing a portion of one of the sticks or rods connected thereto.

Fig. 7 is a fragmentary elevational view of

parts of the bands and showing the means for detachably connecting said bands.

Fig. 8 is a cross section taken on the line 8-8 of Fig. 7.

Fig. 9 is a perspective view showing a pair of the bands in position upon the head and with hair engaged between the clamping bands.

Fig. 10 is an elevational view of a modified form of one of the hair receiving rods or sticks.

As illustrated in the drawings, my improved apparatus includes a pair of substantially semi-circular bands 2 and 3 of thin resilient metal and each band carries on its inner face a soft pad 5 of felt or analogous material.

Projecting outwardly from the outer face of the band 2 are headed studs 6 that are adapted to be engaged by hooks 7 and the shanks of which hooks pass through eyelets that project outwardly from the upper portion of the band 3 and the shanks of these hooks are threaded for the reception of nuts 12. When these nuts 12 are screwed downwardly unto the threaded portions of the shanks into hooks 7, the bands 2 and 3 are drawn toward each other to grip and compress hair that may be positioned between the adjacent edges of the bands.

Secured in any suitable manner on the outer face of the band 2, are small circular housings 9 and formed in the outer portion thereof is a centrally arranged opening from which projects short radially disposed slots 9' which are disposed preferably 90° apart.

Journalized for rotation within each housing 9, is a ratchet wheel 8 and projecting therefrom outwardly through the central opening in the housing 9, is a stud 15, the outer end of which terminates in a ring or loop.

Adapted to engage the teeth of ratchet wheel 8 is a detent 14 that is carried by the free end of a spring and which latter is secured in any suitable manner within the housing 9.

Under normal conditions this detent prevents ratchet wheel 8 from rotating in a reverse direction.

One end of a hair waving stick or short

rod 10, is provided with a shank that terminates in a loop and this loop is engaged in the loop 15 that projects outwardly from ratchet wheel 8 and thus each stick is mounted so that it may be swung in any direction while hair is being curled thereupon. If desired the surface of each stick or rod may be provided with a spirally disposed groove, as illustrated in Fig. 3.

- 10 In the use of my improved hair waving apparatus, a pair of the bands 2 and 3 are positioned on the head 4 over the hair 16 and said bands are brought together so as to clamp the hair that projects between said bands.
- 15 The bands are now detachably connected by engaging hooks 7 beneath the head studs 6 and the bands may now be drawn into clamping engagement with the hair by tightening nuts 12.
- 20 After the sticks or rods 10 have been heated by any convenient means, the ends of the projecting strands of hair are wrapped around said rods or sticks and the latter may now be rotated so as to wind the strands of hair upon 25 the sticks or rods and during such rotation the ratchet wheels 8 rotate within the housings 9 and said ratchet wheels and the sticks or rods that are connected thereto are held against reverse rotation by the spring pressed 30 detents 14.

Thus each strand of hair may be tightly wound upon a stick or rod and after this winding and wrapping operation has been effected the hair carrying stick or rod may be 35 shifted into a vertically or horizontal position as desired and retained in such position by manipulating the rods or sticks so that the shanks of the loops on the inner ends thereof engage in the slots 9' that radiate from the 40 central opening in housing 9.

Thus the hair wrapped on the sticks or rods is retained in the desired position until said hair has become dry and set.

To disengage the apparatus from the hair, 45 the detents 14 are disengaged from the ratchet wheels 8 to permit the rods or sticks to be reversely rotated so as to be disengaged from the windings of hair and the nuts 12 are unscrewed to such a degree as to permit hooks 50 7 to be disengaged from studs 6 and the apparatus may now be removed from the head.

In Figs. 9 and 10 I have shown a modified construction wherein both ends of a hair receiving stick or rod are flexibly connected to 55 the loops 15 on the ratchet wheels 8 and such construction is employed where it is desired to produce what is known as a croquinole effect in hairdressing.

Thus it will be seen that I have provided a 60 permanent waving pad and stick apparatus that is relatively simple in construction, inexpensive of manufacture, and very effective in performing the functions for which it is intended.

65 It will be understood that minor changes

in the size, form and construction of the various parts of my improved permanent waving pad and stick apparatus may be made and substituted for those herein shown and described without departing from the 70 spirit of my invention, the scope of which is set forth in the appended claims.

1. In a device of the class described, a band adapted to be positioned on the head and a plurality of hair receiving rods pivotally and rotatably connected to said band. 75

2. In a device of the class described, a band adapted to be positioned on the head, a plurality of hair receiving rods pivotally and rotatably connected to said band and means 80 on the band for holding each rod against reverse rotary motion.

3. In a device of the class described, a head engaging band, a series of members mounted for rotation on said band and rods pivotally connected to said rotatably mounted members. 85

4. In a device of the class described, a head engaging band, a series of members mounted for rotation on said band, rods pivotally connected to said rotatably mounted members and means for holding said rotatably mounted members against reverse rotary motion. 90

5. The combination with a head engaging band, of a plurality of hair receiving rods, pivotally and rotatably connected to said band and ratchet and pawl connections between said rods and band. 95

6. The combination with a head engaging band, of a plurality of members mounted for rotary movement on said band, hair receiving rods pivotally connected to said rotatably mounted members, a housing secured to the band and enclosing each rotatably mounted member and each housing being provided with a plurality of radial slots for the accommodation of the inner portion of the rod that is connected to the enclosed rotatably mounted member. 100

7. The combination with a head engaging band, of a plurality of members mounted for rotary movement on said band, hair receiving rods pivotally connected to said rotatably mounted members, a housing secured to the band and enclosing each rotatably mounted member, each housing being provided with a plurality of radial slots for the accommodation of the inner portion of the rod that is connected to the enclosed rotatably mounted member and means within the housing for holding said rotatably mounted member against reverse rotation. 110

GRACE M. HUTCHBY.
